Des. 894

Thomas Ball, of Boston, Mass:
Letters Patent No. 894, Dated June 9, 1857.

The schedule referred to in these Letters Patent, and making part of the same.

To all persons to whom these Presents shall come:

Be it known that I, Thomas Ball, of Boston, in the County of Suffolk, and State of Massachusetts, have produced a new and original design for a bust of Napoleon Bonaparte, and I hereby declare that the following description taken in connection with the accompanying drawings hereinafter referred to forms a full and exact specification and representation of the same.

The accompanying drawing, which is a front view shows my new design for a bust of Bonaparte. a, a, is the pedestal. The body is represented as covered with a military coat b, b, displaying one epaulet c, the other epaulet and part of the coat being covered by drapery d. On the left breast are the grand crofs e, and smaller ones f, f, depending from a button g.

Having thus described my new design I shall state my claim as follows:

What I claim as my invention or production and desire to have secured to me by Letters Patent, is the new design for a bust of Napoleon Bonaparte, as hereinabove described and represented in the drawing.
